UNITED STATES PATENT OFFICE

SABURO M. MORIYA, OF WILMINGTON, DELAWARE

MATCH BOOK

Application filed June 11, 1930. Serial No. 460,394.

This invention relates to improvements in book matches, and more particularly to the forming of a compressible walled slot at the base of the book having oppositely disposed 5 match striking surfaces between which a match will be inserted, and the said walls slightly compressed, after which the match will be quickly withdrawn from the slot with a consequent igniting of the same.

10 An object of the invention is to provide an improved form of match book in which a compressible slot is formed having its opposite surfaces covered with a match igniting material, whereby a match may be inserted 15 therein and ignited by withdrawal therefrom, without any chance of igniting the remainder of the matches in the book as is often the case in the usual form of book matches.

20 Another object of the invention is to provide an improved match book having spaced rows of matches positioned therein, and the formation of a compressible igniting slot on the lower outside surface of the book in which 25 the matches may be inserted and withdrawn to ignite the same.

A still further object of the invention is to provide an improved match book with a plurality of spaced rows of matches, and 30 with an external reinforced compressible match igniting slot for positively and safely igniting the matches after the same have been removed from the book.

35 Other objects will appear as the description proceeds.

In the accompanying drawings which form a part of my application,

Figure 1 is a perspective view of my improved match book;

Figure 2 is a vertical sectional view through my improved match book;

Figure 3 is an enlarged vertical sectional view through the lower portion of my match book showing the positioning of the fingers when a match is about to be ignited, and

Figure 4 is a sectional view on the line 4-4 of Figure 2.

Like characters of reference are used 50 through the following specification and the

accompanying drawings to designate corresponding parts.

In carrying out my invention, I provide a match book 1 comprising a back 2 having a flap 3 secured thereto and movable towards and away from the same. The base of the back 2 is looped to form a W-shape portion having spaced slots 4 in which two rows of safety matches are securely held by the clips 5, and extend in substantially parallel relation with the said back. The intermediate striking slot 6 is opened away from the match book and formed by the adjacent sides of the match holding slots 4. Strips of match igniting material 7 are secured to the opposite walls of the slot 6 in spaced relation and are spaced with respect to the inner portion or bottom of the slot, so that a match may be detached from the book, the flap closed, and the match head inserted within the slot 6 beyond the strips of igniting material. A slight pressure of the fingers on the opposite sides of the book at the base thereof will be effected, and the match stem pulled quickly out of the slot 6. Thus, it will be seen that there will be some momentum gained in the first movement of the withdrawal of the match before the head thereof comes in contact with the igniting material, after which the match will be ignited as it leaves the confines of the igniting slot.

It will be apparent that the folds in the bottom of the match book will cause the flap 3 to normally be quite securely retained within the locking groove when the book is closed. The double row of matches in the book will give sufficient bulk to the book to provide for a firm grasping of the same when a match has been inserted within the igniting slot prior to its being withdrawn.

Many minor changes in detail of construction may be resorted to without departure from the spirit of the invention.

Having thus described my invention what I claim as new and desire to secure by Letters Patent of the United States is:

1. A match book comprising a cover member, a plurality of compressible slots formed in the base thereof, the outermost slots opening towards the interior of said cover mem-

ber and the intermediate slot opening in the opposite direction therefrom, spaced rows of matches supported within said outermost slots, and match striking strips secured to the opposite walls of said intermediate slot in spaced relation to the bottom of said slot.

2. A match book comprising a cover member, a plurality of compressible slots formed in the base thereof, matches received within the outermost slots, and match striking strips secured to the opposite sides of the intermediate slot in spaced relation to its opposite ends.

3. A match book comprising a cover member having a foldable flap closure, a compressible W-shape fold in the base thereof, matches carried in the outermost portions of said fold, match igniting surfaces on the inner portion of said fold, and means for holding said flap in closed position.

4. In testimony whereof I affix my signature.
SABURO M. MORIYA.
